GARMENT

Benjamin Strenger and Dora Herdan,
Philadelphia, Pa.

Application August 15, 1942, Serial No. 454,964

1 Claim. (Cl. 2—115)

The present invention relates to garments and more particularly to improved means for maintaining a garment such as a man's shirt or a woman's waist in proper position at the waistline of the wearer.

An essential feature of the invention consists in forming the body of the garment with an integral depending short yoke, and folding the fabric over and upwardly on one side of the garment and then downwardly to provide a circumferentially disposed flat pleat of substantial width at the waist line. The pleat is secured to the body of the garment by stitching spaced from the upper edge of the pleat so that the portion of the pleat above the stitching on one side of the garment, constitutes an upwardly and outwardly or laterally extending flexible projection which extends completely around the garment, so as to engage the body of the wearer or an enclosing garment in order to resist creeping of the garment upwardly, and which would otherwise give an objectionable and unsightly appearance to the garment.

Other objects and advantages of the invention will become apparent from the following description when taken in conjunction with the accompanying claim and drawing.

Referring to the drawing:

Figure 1 is a front view of a shirt having my invention associated therewith, and showing one of the front flaps raised.

Figure 2 is an enlarged sectional view taken substantially along the line 2—2 of Figure 1, and

Figure 3 is an enlarged sectional view of a modified form of the invention.

Referring to the drawing, in which like numerals indicate like parts in the several views, 10 designates a garment, which for the purpose of illustration, is shown as a man's shirt made of any suitable fabric. The front of the body 11 is divided into overlapping flaps 12 and 13. One of the flaps such as 12 has secured thereto spaced vertically disposed fastening means such as the buttons 15 arranged to cooperate with the buttonholes 16 on the other flap 13 for fastening the flaps together.

As shown in Figures 1 and 2, the body 11 has an integral short yoke 16 depending therefrom. The fabric between the body 11 and the yoke 16 is folded over and upwardly at 17 for a substantial distance (Fig. 2) on the inner side of the garment, then is turned downwardly at 18 to produce a circumferentially disposed thickened flat pleat 19 extending completely around

the garment at the waist-line of the wearer. Spaced longitudinal upper and lower rows of stitching 20 and 21 respectively secure the pleat 19 to the body 11 of the garment. However, any other suitable types of stitching may be used. The upper row of stitching 20 is spaced from the upper edge of the pleat 19 so that the portion of the pleat above the same on the inside of the garment, constitutes an upwardly and inwardly extending flexible projection 22 coextensive in length with the garment, and so arranged as to engage or comfortably press against the body of the wearer to resist firmly the tendency of the shirt to creep upwardly or pull away from the trousers. The lower outwardly projecting flexible portion 17 is similarly spaced from the stitching 21 and is arranged to engage an enclosing garment to prevent the garment slipping downwardly. Thus, means are provided on the inside and outside of the garment to resist the garment creeping upwardly or slipping downwardly at the waistline. The portion of the pleat 19 between the stitching 20 and 21 is smooth and flat and provides a reinforcement for the garment between the body and the yoke at a point subjected to the greatest strain.

Suitable fastening means such as the spaced buttons 23 and 24 are secured to the outer surface of the pleat 19 on the flap 12 (Fig. 1) and are arranged selectively to engage a buttonhole 25 formed in the portion of the pleat on the opposite flap 13 and constitute fastening means secured to the pleat 19 for adjusting the peripheral length of the pleat to insure a snug and proper fit over the hips of the wearer of the garment without any binding effect.

Manifestly, various other types of fastening means such as snaps, hooks or the like may be used for fastening the front flaps and the opposite sides of the pleat. Moreover, any number of longitudinally spaced fasteners may be provided so that the shirt will properly fit the wearer at the waist-line.

It will be seen that the short integral yoke 16 affords a substantial saving in the material required to make the shirt, as compared with an ordinary shirt which has a long shirt tail, much of which serves no useful purpose, and is really a waste of material. Moreover, one or more rows of stitching may be used for securing the pleat to the body of the garment and the stitching may include up and down stitches or quilting which terminate short of the upper edge of the pleat so as to insure the formation of the flexible circumferentially disposed projection 22.

In the modified form of the invention shown in Figure 3, the body 26 of the shirt or garment has an integral short flap 27, and the garment between the body and the flap is folded outwardly and upwardly as at 28 for a substantial distance, and downwardly and outwardly at 29 to form the flat thickened pleat 30 which extends completely around the outside of the garment at the waistline. The pleat 30 is secured to the outside of the garment by the spaced rows of stitching 31 and 32 and the portion of the pleat above the upper row or stitching 31 extends outwardly therefrom to form a flexible projection 33 arranged to engage an enclosing garment so as to prevent the shirt from creeping upwardly or outwardly relative thereto. The lower flexible portion 28 on the inside of the garment is arranged to engage the body of the wearer to prevent the garment from slipping downwardly. It will be seen that the flexible projections 28 and 29 provide means for insuring the garment being held in proper position at the waistline.

While the invention has been shown associated with a man's or boy's shirt to maintain the lower portion thereof in place, it will be manifest that the same may also be efficiently used with a woman's or girl's waist or blouse. It will be observed that in both forms of the invention the pleat is provided with an upwardly extending integral free portion or projection which extends outwardly from one side of the pleat and a downwardly extending flexible portion which coacts with the upwardly extending

portion to maintain the shirt or waist within the trousers or skirt of the wearer and thus provides simple, efficient and positive means for preventing the lower portion of the garment from creeping upwardly or slipping downwardly and thus preventing an unsightly or objectionable appearance.

It will be understood that the several forms of the invention shown are merely illustrative of preferred embodiments and that the invention comprehends within its scope such changes as fall within the following claim.

We claim:

A garment formed from a single continuous piece of fabric including a body having a short yoke depending therefrom, said fabric between the body and the yoke being folded over and upwardly a substantial distance on one side of the garment, then downwardly to produce a circumferentially disposed flat pleat at the waistline of the wearer, and stitching securing the pleat to the garment, said stitching being spaced from the upper and lower edges of the pleat so that one end portion of the pleat extends inwardly and the other outwardly from the garment to provide flexible projections, one of which projections is arranged to engage the body of the wearer and the other an enclosing garment so as to resist the garment creeping upwardly or slipping downwardly at the waistline.
